HAIR CURLER

Harry H. Klein, New York, N. Y.

Application April 25, 1936, Serial No. 76,358

7 Claims. (Cl. 132—41)

This invention relates to hair curlers, and particularly to the type wherein a bar, arm, and band are cooperatively hinged to allow curling of the hair around the bar and arm, and retain it in curled state.

The principal object of the invention is to provide a conveniently and economically manufacturable, conveniently utilizable, efficient, and improved hair curling device of the above type.

10 Another object is to provide a hair curler of the above type with improved means for positively and efficiently engaging its hair retaining band to its hair curling bar, for improving the operation and resulting performance of the hair 15 curler.

Other objects and advantages will hereinafter appear.

In the accompanying drawing,—

Fig. 1 is a side elevation of the hair curler 20 of this invention.

Fig. 2 is a cross-sectional plan view, showing the portion of the hair curler for engaging its hair retaining band to its hair curling bar.

Fig. 3 is a fragmentary plan view showing a 25 modification of the improvements illustrated in Fig. 2.

Fig. 4 is a fragmentary cross-sectional plan view, showing another modification of the improvements.

30 Fig. 5 is a cross-sectional side elevation of the improvements shown in Fig. 4.

The hair curler 1, Fig. 1, comprises a tubular bar 2, a concave arm 3, and a retaining band 4 preferably made of wire. Said bar, arm, and 35 band are hingedly connected to each other as shown at 5, whereby the bar, arm, and band are swingable relatively to each other about a common axis, as illustrated by the dot and dash lines. The bar 2 and arm 3 are provided with 40 finger-pieces 6, 7, and a spring, as shown, bears against said finger pieces, whereby the bar 2 and arm 3 are normally impelled to bear pressingly against each other as shown, while when the finger-pieces 6, 7 are pressed toward each 45 other the arm 3 is swung away from the bar 2 to the position shown by the dash and dot lines.

The end portion 8 of the band 4 is formed straight and right angularly to the bar 2, and it carries a device 9 wherewith to engage the band 50 to the arm, as required for the operation of the hair curler. Said device consists of a spherical metallic shell 10 mounted over and around the band-portion 8 and having relatively large 55 openings 11 that are coaxial with the band portion. The shell 10 is filled with a body 12 of pli-

able rubber having a bore 13 constituting a bearing to render it revolvable about the band-portion 8 which thus serves as an axle shaft for the entire device 9. On exerting any pressure by rim 14 upon the equatorial area of the shell 10 it 5 will be shifted eccentrically toward the shaft 8, as shown by the dash and dot lines, Fig. 2, due to the compressibility of the rubber body 12 therewithin, while upon release of such pressure the shell 10 will at once spring back to the normal coaxial position shown, owing to the resiliency of its rubber body. When the band 4 is swung away from the bar 2 the device 9 is in its normal or coaxial position shown in Fig. 2, but when the band is swung toward the bar 15 the equatorial portion of shell 10 strikes the terminal rim 14 of tubular bar 2, which thereupon presses and actuates the shell to a position eccentrically to the shaft 8 and successively causes the shell 10 to spring back to normal 20 coaxial state and to fall into and in locking engagement with the terminal of bar 2, as shown in Fig. 1. Swinging of the band 4 out of alignment with the bar 2 will of course produce a reversal of the above described operation and 25 a consequent disengagement of the band from the bar. When utilizing this hair curler, the arm 3 is first disposed to the open inoperative position, shown by the dash and dot lines, Fig. 1, the end of the hair is then placed between it 30 and the bar 2, then said end is gripped by releasing the arm to the spring-pressed position shown against the hair and bar 2, and then the curling of the hair is continued around the closed arm and bar, after which the band 4 is 35 swung into engagement with the bar to maintain the hair in the curled condition as required.

According to the modification shown in Fig. 3, the engaging device 9a consists of a spiro-helical wire spring 15, the terminals 16 of which form 40 a bearing about the band-shaft portion 8 of the band 4, whereby the spring tuft 15, having the general outline of a spherical body, is revolvable about the shaft 8 to and around which it is thus mounted. When swinging this band 4 into 45 alignment with the bar 2 and away therefrom it will engage with it and disengage therefrom in the manner described above in connection with the device 9, Figs. 1, 2.

In the modification shown in Figs. 4, 5, the 50 engaging device 9b has a shell 10 similar to that shown in Fig. 2, which shell is filled with a flat metal spiral spring 17, the inner terminal end 18 of which forms a bearing about the band-shaft portion 8 of the band 4 and its outermost 55

hoop 19 is flared against the inner wall of the shell 10, whereby the latter is revoluble about the shaft 8, and when the band 4 is swung into cooperative alignment with the bar 2 this device 5 9b will engage with it in the above described manner and accordingly disengage therefrom when the band is swung away.

Variations may be resorted to within the scope 10 of the invention, and portions of the improvements may be used without others.

Having thus described my invention, I claim:—

1. A hair curler having the combination of a hair winding bar, a hair retaining band having an end serving as an axle, said band and bar 15 being hinged to each other, a device carried by the said axle including a shell, and a filler of rubber within said shell being mounted on said axle to permit the shell to move in a motion of translation to a position eccentrically to the axle 20 and successively to a position concentrically with the axle for engaging with and disengaging from the end of said bar.

2. A hair curler having the combination of a hair winding bar, a hair retaining band having 25 an end serving as an axle, said band and bar being hinged to each other, a device carried by the said axle including a shell, and a filler of elastic material within said shell being mounted on said axle to permit the shell to move in a motion of translation to a position eccentrically to the axle and successively to a position concentrically with the axle for engaging with and disengaging from the end of said bar.

3. A hair curler having the combination of a hair winding bar, a hair retaining band having 35 an end serving as an axle, said band and bar being hinged to each other, a device carried by the said axle including a shell, and a resilient member within said shell being mounted on said axle offering resistance to compression upon the 40 periphery of the shell to permit the shell to move in a motion of translation to a position eccentrically to the axle and successively to a position

concentrically with the axle for engaging with and disengaging from the end of said bar.

4. A hair curler having the combination of a hair winding bar, a hair retaining band, said band and bar being hinged to each other, a device carried by the end of said band for engaging the end of said bar, said device including a shell surrounding said end of the bar, and a spiral spring located within said shell being mounted about said end of the band offering 5 10 resistance to compression upon any part of the periphery of said shell.

5. A hair curler having the combination of a hair winding bar, a hair retaining band, said band and bar being hinged to each other, a device carried by the end of said band for engaging the end of said bar, said device including a shell surrounding said end of the bar, and a spring located within said shell being mounted about 15 20 said end of the band offering resistance to compression upon any part of the periphery of said shell.

6. A hair curler having the combination of a hair winding bar, a hair retaining band, said band and bar being hinged to each other, a device carried by the end of said band for engaging the end of said bar, and said device including a spiro-helical spring surrounding said end of the band for resiliently engaging the terminal of said 25 30 bar.

7. A hair curler having the combination of a hair winding bar, a hair retaining band having an end serving as an axle, said band and bar being hinged to each other, a device carried by said axle for engaging the end of said bar, said device including a spherical element adapted to press with its equatorial area upon the end of said bar, and said element having resilient means to permit it to move in a motion of translation to a position eccentrically to said axle and successively to a position concentrically with the axle 40 for engaging with and disengaging from the end of said bar.

HARRY H. KLEIN.
